UNITED STATES PATENT OFFICE.

FRANK J. ANDERSON, OF GREAT FALLS, MONTANA.

DETACHABLE BUTTON.

1,219,902.

Specification of Letters Patent. Patented Mar. 20, 1917.

Application filed October 14, 1914. Serial No. 866,699.

To all whom it may concern:

Be it known that I, FRANK J. ANDERSON, a citizen of the United States, residing at Great Falls, in the county of Cascade, State 5 of Montana, have invented certain new and useful Improvements in Detachable Buttons; and I do hereby declare the following to be a full, clear, and exact description of the invention, such as will enable others 10 skilled in the art to which it appertains to make and use the same.

This invention relates to improvements in garment suspending devices and particularly to a clasp for engagement by the tab end 15 of suspenders.

One object of the invention is to provide a simple and novel device of this character which can be quickly and easily attached to or detached from the trousers band.

Another object is to provide a device of 20 this character which will be efficient in its operation to hold the suspender in proper engagement therewith.

Other objects and advantages will be apparent from the following description when taken in connection with the accompanying drawing.

In the drawings:

Figure 1 is a perspective view of my invention, showing the same attached to the trousers band, with the suspender in engagement therewith,

Fig. 2 is an enlarged vertical sectional view longitudinally through the device in Fig. 1, and

Fig. 3 is an enlarged edge view of the device removed from the trousers band.

Referring particularly to the accompanying drawing, 10 and 11 represent two plates, 40 the upper ends of which are secured together by the pin 11' and bent so as to extend downwardly a short distance in parallel relation with the remainder of the plates. The extremity of the downturned portion 45 of the plate 11 is bent inwardly at right angles toward the plate 10 as indicated at 12 while the corresponding end of the plate 10 is bent at right angles as at 13 in a direction toward the end of the plate 11 and in 50 a plane above the inturned portion 12. The portion of the plate 10 above the angularly bent end is slightly offset to form a recess 14. A guard lever 15 is provided with a slot 55 16 which receives both of the portions 12 and 13 therethrough when the lever is in

closed position, the upper angularly extending end 17 being disposed within the before-mentioned recess 14. The portion of the plate 10 between its points of connection with the plate 11 and the offset portion is 60 possessed of sufficient resiliency to bear against the portion 17 and hold the member 15 firmly and yieldably against the outer face of the plate 10. As will be readily understood, the portions 12 and 13 act as a 65 pivot through the slot 16 so that the guard 15 can be easily swung away from the plate into position to enter the buttonhole opening of the suspender tab. Secured to the inner face of the body portion of the plate 11 70 is a stud 20, the upper and lower faces of which are formed with barbs 21, the outer end of the said stud being sharpened so that the same can readily penetrate the cloth of the trousers band. In the plate 10 at a point 75 directly opposite to the stud 20 are struck out the tongues 22 in such manner that an entrance opening 23 thereby is formed to receive the toothed end of the stud 20, the ends of the tongues being adapted to engage 80 with the barbs to hold the plates firmly clamped on opposite sides of the trousers band. Secured to the outer face of the plate 10 is an ornamental plate 24 which covers 85 the tongues 22 but is spaced from the plate a sufficient distance to permit the stud to pass beyond the tongues a slight distance.

In the operation of the device the plates 10 and 11 being normally moved away from each other, the trousers band is inserted 90 therebetween and then the stud 20 forced through the cloth and through the opening 23 until the barbs of the stud are properly engaged with the tongues 22. The device is then firmly attached to the trousers band. 95 To engage the suspender end with the device, the member 15 is swung outwardly away from the plate 10 and inserted through the button-hole 18 of the tab. The tab will thus ride up into the space inclosed by the 100 curved portion of the plates 10 and 11 and the weight of the trousers be taken at this point. The guard 15 is then swung back against the plate. The resiliency of the end of the plate 10 is such that it will hold the guard outwardly away from the plate as well as against the plate. It will be noted that the portion 17 is of a width slightly less than the length of the recess 14, and that the opening or slot 16 is wide enough 110

to permit the passage of the lower part of the portion 12 to pass therethrough when the guard is swung upwardly.

It will also be noted that the difference between the inner vertical wall of the recess 14 and the opposite vertical portion of the end of the plate 11 is less than the width of the portion 17 so that when the member 15 is swung into position against the plate 10, this portion 17 presses against the before-mentioned portions of the plates 10 and 12 and moves the resilient end of the plate 10 away from the plate 11. The member 15 will thus be held against accidental outward movement away from the plate.

What is claimed is:

A clasp fastener comprising in combination, a base plate having an overturned portion overhanging its body, a second plate se-

cured to the first plate and also having an overhanging portion fixed within the overturned portion of the first plate, the overhanging ends interengaging to provide a resilient bearing, and a guard lever having an angularly shaped pintle mounted within said resilient bearing, the angularly shaped pintle acting to spread the bearing during the motion of the guard lever into its open or closed position and said resilient bearing closing around the pintle to hold the guard lever in either its open or closed position.

In testimony whereof, I affix my signature, in the presence of two witnesses.

FRANK J. ANDERSON.
